W. D. JOYCE

HEADLIGHT

Filed March 25, 1924

William D. Joyce,
Inventor

By *Clarus et. al.*
Attorney

UNITED STATES PATENT OFFICE.

WILLIAM D. JOYCE, OF ANTONITO, COLORADO.

HEADLIGHT.

Application filed March 25, 1924. Serial No. 701,773.

To all whom it may concern:

Be it known that I, WILLIAM D. JOYCE, citizen of the United States, residing at Antonito, in the county of Conejos and State of Colorado, have invented certain new and useful Improvements in Headlights, of which the following is a specification.

This invention relates to new and useful improvements in headlights and has for its 10 principal object to provide a simple and efficient device wherein the rays of light will be directed outwardly from the headlight in a substantially straight path and further directed onto the road, thus preventing an approaching driver from being blinded by the 15 glare from the headlight.

Another important object is to provide a headlight of the above mentioned character, wherein an elongated shade is provided 20 on the front of the headlight for causing the rays of light to be directed downwardly onto the road and to prevent the light rays from being directed upwardly so as to interfere with the driving of approaching vehicles.

A still further object of the invention is 25 to provide a headlight of the above mentioned character, wherein the lens holder is of such a construction as to permit the same to be readily disengaged from its normal position to permit access to the interior 30 of the headlight for replacing the bulb therein, means being further provided for securing the lens holders in a substantially rigid position on the headlight when in use.

A still further object of the invention is 35 to provide a headlight of the above mentioned character, which is simple in construction, inexpensive, strong and durable and furthermore adapted for the purposes for which it is designated.

Other objects and advantages of this invention will become apparent during the course of the following description.

In the accompanying drawing forming a 45 part of this specification, and in which like numerals designate like parts throughout the same,

The figure is a cross sectional view of my improved headlight.

In the drawing wherein for the purpose 50 of illustration is shown the preferred embodiment of my invention, the numeral 1 designates the casing which is formed of any suitable metallic material and is substantially cylindrical. The casing 1 has its front

face provided with the upstanding wall 2 which closes the lower half thereof in the manner clearly shown in the drawing. Adapted to be hingedly supported on the upper edge of the upstanding front wall 2 60 on the transversely extending pin 3 is the lens holder 4. The same is preferably of semi-circular form to conform to the upper half of the front face of the casing and is adapted to support therein the usual lens 5 in any well known manner. For the purpose of holding the lens holder 4 and the lens 5 mounted therein in an operative position on the front face of the casing, I provide the top of the casing with a spring 65 catch 6 which extends through a suitable opening provided in the top of the casing adjacent the forward edge thereof and will engage the upper portion of the lens holder in the manner clearly shown in the drawing. 70

Supported in the casing 1 and extended from the top thereof to the rear wall 7, thence to the bottom of the casing and finally upwardly into engagement with the front wall 2 is the reflector 8. Supported by the 80 rear wall 7 of the casing 1 and extending into the reflector 8 is the usual electric lamp or bulb 9 whereby a source of light will be provided in the well known manner.

Formed integrally with the casing 1 and 85 extending forwardly from the front face thereof preferably from the upper open half of the same is the curved shade 10. The bottom edge 11 of the curved shade 10 extends substantially in the same horizontal 90 plane as the upper edge of the front wall 2 of the casing in the manner as clearly shown in the drawing. The front shade 10 may also be formed of colored glass and the inner surface of the shade is provided with a reflector surface and I do not wish to limit myself to the particular manner in which the shade is constructed or the material 95 from which the same is formed.

With the parts arranged as shown in the 100 drawing, the rays of light from the lamp 9 will be directed downwardly to the bottom of the reflector 9, thence upwardly to the upper portion of the reflector and the rays of light will then be caused to pass through 105 the lens 5, some of the rays of light will be directed onto the road while other of the rays will be deflected by the curved shade 10, thus preventing the rays of light from 110 being directly upwardly and causing the

glaring of the light which is dangerous to drivers of approaching vehicles. By directing the rays of light in the manner as above described, the road will be illuminated directly in front of the vehicle thus enabling the operator to readily have a full and good view of the road and furthermore there will be no tendency of the rays of light to cause confusion with approaching vehicles.

10 The purpose of providing a lens holder which is hinged in the manner heretofore described is to provide a means whereby the lamp 9 may be readily removed from the 15 socket in the casing and replaced whenever necessary. In use, the lens holder will be held in position by means of the spring latch 6 against any relative swinging movement.

16 20 The simplicity of my device enables the same to be manufactured at a very low cost and will also be strong and durable and very efficient in its operation.

25 While I have shown the preferred embodiment of my invention, it is to be understood that various changes in the size, shape and arrangement of parts may be resorted to without departing from the spirit of the invention and the scope of the appended 30 claim.

Having thus described my invention, what I claim is:

A headlight comprising a light casing embodying a flat circular peripheral wall, a discular concavoconvex rear wall, and a 35 semi-discular front wall, the upper edge of said front wall terminating slightly below the focal center of the casing, a semi-discular lens rim hingedly connected at its bottom to the upper edge of the front wall, a correspondingly shaped lens carried by said rim and extending over the upper half of the front of the casing to restrict the light beam projected therethrough, a reflector in said casing, and a light also in the casing at the 40 approximate focal center thereof, and a relatively long forwardly and downwardly curved light shade formed integral with the upper half of the casing and having its lower edges terminating in a plane with the 45 upper edge of the aforesaid front wall of the casing, said shade being formed at the center of its top and at its point of juncture with the casing with an opening, and a resilient latch carried by the casing and having a nose projectable through said opening and engaged with the lens rim to maintain the latter in operative position.

In testimony whereof I affix my signature.
WILLIAM D. JOYCE.
